KARL KOLLER, OF BUDAPEST, HUNGARY

PRESSURE GAS PRODUCER

Original application filed July 8, 1924, Serial No. 724,876, and in Czechoslovakia and Germany July 14, 1923.
 Divided and this application filed August 16, 1929. Serial No. 386,356.

- In pressure gas producers the mixture of steam and air required for gasifying the fuel enters the producer shaft through a distributing body which projects over the ash-pan. 5
- 5 The constructional forms made hitherto all have the disadvantage, that the mixture of steam and air is not utilized in the producer shaft in such a manner as is necessary for getting the best result from the fuel or for 10 producing a quality of gas corresponding to the fuel. Hitherto such distributors have been divided substantially into two groups. One of these groups comprises a short outlet pipe which is substantially the same size as 15 the supply pipe for the steam and air mixture which passes out through openings provided in the outlet pipe. These outlet openings are usually formed between conical rings which overlap one another like louvres 20 and which provide a total outlet for the mixture of steam and air of such a cross-sectional area that during the operation of the producer the difference in pressure between the fluid flowing within the interior of the distributor and the pressure existing in the surrounding producer shaft will be only just 25 sufficient to enable the mixture of steam and air to flow out effectively. When the producer is out of operation (i. e. when the producer shaft is empty and closed by the ordinary water seal), the outlet openings in the distributor as hitherto constructed will form 30 such communicating passages between the interior of the distributor and the empty producer shaft that they will allow the mixture of steam and air to pass freely according to a law by which the flowing fluid shortly after 35 leaving the distributor follows a practically vertical upward course.
- 40 In practice the proportions hitherto used between the total cross-sectional area of the outlet openings in the distributor and the internal cross-sectional area of the same lead to the following disadvantages: The 45 outflow of the mixture of steam and air from the openings in the distributor is determined, when the producer is in operation, by the resistance offered in the producer shaft by the fuel and thermochemical phenomena. As explained above the fluid will pass almost ver- 50
- tically upwards through the outlet openings shortly after leaving the distributor when only the resistance offered by the surrounding air has to be overcome. This characteristics of the flow will not be substantially 55 changed when the producer is in operation, as the fluid will flow not in accordance with theory but in a direction determined by the places of least resistance in the shaft. (The more homogeneous the fuel, with the shaft 60 filled to the same height, the nearer will this direction of flow approximate in practice to the theoretical flow referred to above.) The consequence of this is that unburnt fuel will 65 pass through the producer. This resulted in 65 the distributor in the form of a short pipe being abandoned and an ordinary grate being used extending almost up to the wall of the producer, so that the air could also have effective access to those parts of the fuel situated in proximity to the wall of the producer and thus promote combustion of the fuel at 70 the margin of the fuel bed.
- The distributors belonging to the second group above referred to consist of chambers 75 placed on the supply pipe and having a stepped conical shell the lowest part of which reduces the internal cross-sectional area of the producer shaft to such an extent that considerable resistance is offered to 80 the passage of clinker and ash through the producer. Such distributors have outlet openings which allow of the fluid obtaining a nozzle velocity (perforated grate) and the path of the air corresponding to such a velocity will follow a parabola, it is a necessary condition for the proper operation of the producer that for each particle of air 85 this path up to the producer wall will be of such a length that the air will be used up 90 before reaching the producer wall. If this is not the case, the still unused air will flow upwardly along the producer wall, will cause marginal combustion of the fuel and combustion of the gas already produced. 95 Attempts have been made to prevent this marginal combustion by considerably raising the height of the fuel bed more particularly at the margins by means of special charging appliances. Marginal combustion 100

however is not to be entirely avoided by this means, this increase in the height of the fuel bed only temporarily suppressing it if the quantity of steam and air mixture blown through remains the same, and finally a reduced output of the producer would be the only way out of the difficulty.

If such chamber-like distributors are provided with perforations not having the character of nozzles, these constructions suffer from the disadvantages alluded to above to a still greater extent.

The present invention is based on the recognition of the fact that on the one hand the free annular space between the distributor and the producer wall must be as large as possible for enabling the clinker and ash to pass through freely into the ash pan, hence the distributor must have the character of a short pipe as described above, while on the other hand the outlet openings must be in the wall of a cylindrical distributor and ratio of the total cross-sectional area of these outlet openings to the internal cross-sectional area of the cylindrical distributor must be such that parallel streams of fluid will result which follow the course of flat parabolas and have the required nozzle velocity, so that the fluid is already used up when it arrives at the wall of the producer. As regards the desired degree of outlet velocity this arrangement has the further advantage, that the residual velocity of the fluid in the distributor from the velocity in the supply pipe is increased by the nozzle action.

The invention is illustrated by way of example in the accompanying drawing wherein:

40 Figure 1 is a cross-sectional elevation through a producer; and

Figure 2 is a cross-sectional elevation of the distributor on an enlarged scale.

Similar numerals refer to similar parts throughout the several views.

The gas producer comprises a producer gas generating shaft 1 having an annular skirt 2 which dips into the rotating ash-pan 3 which is filled with water and moves the slag and ashes as they pass out of the producer shaft against a lateral scraper along which the slag and ashes are guided out of the producer.

The distributor is of cylindrical shape and 55 consists of separate rings 11 of uniform size arranged one above the other and spaced apart by means of ribs or the like so as to leave circumferential slots between them. The distributor is covered by a cap 12. The 60 fuel and the ashes are supported by the ash-pan 3. By building up the distributor from a number of rings of uniform size, the height of the distributor can be varied while maintaining its cylindrical character, so that the 65 combustion zone in the producer shaft can

be adjusted to suit the conditions under which the producer is operated.

The invention also comprises the provision of means for adjusting the effective total cross-sectional area of the nozzle outlet openings in order to enable the velocity of the mixture of steam and air flowing out from the distributor to be regulated so as to enable the incandescent or combustion zone of the fuel bed proper to be constrained to occupy a predetermined position to suit the actual conditions under which the producer is operated for the time being. By this means the regulation of the velocity can be adjusted so that the producer shaft is utilized directly as a low temperature distillation chamber for the fuel. The preferred form of regulating means consists of a cylindrical valve arranged inside the distributor will be described subsequently.

Another constructional form of the distributor has for its object to render the regulation exceedingly simple, the mixture of steam and air introduced into the distributor and passing through it having its direction of flow reversed before entering the producer shaft, whereby the distributor is cooled and so protected from damage.

The rings 11 have radially extending nozzle apertures 13 and the cap 12 may also be provided with such nozzle openings as shown at 14. A hollow cylindrical slide valve 15 is inserted in the chamber formed by the built up rings 11, the wall of which valve, is provided with perforations 16 and gearing 26 for adjusting the same. The mixture of steam and air entering the cylindrical valve 15 passes through the perforations 16 and the nozzles 13 into the solid fuel bed in the producer body. By adjusting the cylindrical valve 15 the relative positions of the perforations 16 and of the nozzles 13 may be varied. Thus, the incandescent or combustion zone of the fuel bed, two extreme positions of which 17 and 18 are shown in the drawing, will have the shape of the upper portion of a paraboloid, which is substantially determined by the flow of steam and air mixture emerging from the lowest nozzles.

The advantage of this mode of regulation is obvious, if it be considered that with the same producer, using the same kind of fuel and with the same quantity of fuel passing through the producer, it is possible to maintain the incandescent or combustion zone in any desired position in the producer body between certain limits and thereby to increase the height of the fuel bed above this combustion zone to such an extent that in this space low temperature distillation may already take place. This provides the great advantage that in some cases it will be possible entirely to dispense with separate additional retorts for the producer.

The incandescent or combustion zone with its means of regulation prevents the passage of unburnt fuel through the producer. It may be found, however, that unburnt fuel is passing through the gas producer, owing to the fact that the paraboloid of flow enclosed by the mixture of steam and air is too steep, more particularly in the case of fuel which does not readily ignite, so that unburnt or undistilled coal can pass through between the edge of the incandescent or combustion zone and the inside of the producer wall (see combustion zone 17 with the gas cut-off curve 19, extending from the combustion zone to the inside wall of the producer preventing the admission of air to the distillation space). In such cases the paraboloid of flow is simply flattened by adjusting the velocity of the mixture of steam and air flowing into the producer shaft, whereby the incandescent zone is lowered and caused to extend to the inside wall of the producer and the entire charging or distilling shaft is thus masked over its whole cross-sectional area by the incandescent or combustion zone.

This mode of regulation will obviously entail no alteration in the quantity of air supplied, as the alteration of the shape of the paraboloid of flow depends solely on the regulation of the effective cross-sectional area of outlet nozzles for the mixture of steam and gas.

In order to effect the discharge of the ashes in an efficient manner and thereby ensure the combustion zone being maintained in the required position, cutters or the like 24 are provided on the ash-pan which coact with cutters 25 fitted on the immersed ring or skirt 2 and extend into the interior thereof in such a manner that on the ash pan and outside the immersed ring a breaking or shearing device is formed which reduces the lumps of slag expelled radially or acted on in such a manner as to tend to move radially. By this means the advantage is obtained that stripping of the ashes and reduced slag takes place not only at the known strippers or scrapers 4 but also by means of the cutters 24, 25 arranged on the immersed ring, so that these cutters acting as slag shearing means in conjunction with the known cutters or the like arranged on the ash-pan, on the one hand effect the uniform exit of the ashes and slag from the producer at its entire periphery and on the other hand reduce the lumps of slag in the desired manner.

This arrangement will in practical operation make itself effective in that the incandescent zone is maintained uniformly in the same position, whereby the yield of the producer is considerably increased. Further, the interior of the producer and of the immersed ring adjoining it is rendered entirely free for the passage of ashes and slag, since

the breaking or shearing device is only situated within the confines of the ash pan.

The ash-pan 3 is provided in a known manner with cutters or the like 24 which always operate under water and the skirt 2 is fitted with the known lateral stripper 4.

This is a division of my co-pending application Serial No. 724,876, filed July 8, 1924, now Patent No. 1,728,684, September 17, 1929 for pressure gas producers.

I claim:

1. In a gas producer, a shaft adapted to contain a solid fuel bed, an ash-pan, a short hollow cylindrical distributor having horizontally directed outlet openings for admitting a blast of steam and air to the fuel bed in the shaft, and adjustable valve means to regulate the velocity of the blast issuing from the distributor, said means operating to vary the ratio of the total cross-sectional area of the outlets to the cross-sectional area of the interior of the distributor, and comprising a pair of perforated, cylindrical shells in said distributor relatively revoluble for adjustment and means for adjusting the position of said valve means for the purpose of regulating the blast issuing from the distributor.

2. In a gas producer, a shaft adapted to contain a solid fuel bed, an ash-pan, a short hollow cylindrical distributor having horizontally directed outlet openings for admitting a blast of steam and air to the fuel bed in the shaft, and means to regulate the velocity of the blast issuing from said distributor, said means comprising a valve for varying the effective cross-sectional area of the inlet ends of the outlet openings, and comprising a pair of perforated, cylindrical shells in said distributor relatively revoluble for adjustment and means for adjusting the position of said valve means for the purpose of regulating the blast issuing from the distributor.

3. In a gas producer, a shaft adapted to contain a bed of fuel, a hollow distributor provided with outlet openings for admitting gas-making fluid to said fuel bed, said distributor extending into the bed, and means for varying the area of said outlet openings to vary the velocity of the fluid introduced into said fuel bed, said means comprising a member adapted to be passed over said outlet openings to vary the areas of said outlet openings through which fluid may pass into said fuel bed.

4. In a gas producer, a shaft adapted to contain a solid fuel bed, a hollow distributor provided with outlet openings for admitting gas-making fluid to said fuel bed, said distributor extending into said bed, a shell within said distributor provided with openings adapted to register with said outlet openings, and means for moving said shell relative to the openings in said distributor to vary the effective area of said outlet openings and thus

change the velocity of the fluid passing through said openings into said fuel bed.

5. In a gas producer, a shaft adapted to contain a solid fuel bed, a hollow cylindrical distributor provided with outlet openings disposed in rows, each extending circumferentially about the distributor and the rows being spaced along the height of the distributor, each outlet opening being adapted to admit 10 gas-making fluid to said fuel bed, a cylindrical shell positioned within said distributor provided with openings adapted to register with said outlet openings, and means for rotating said shell to vary the effective 15 area of said outlet openings, and thus change the velocity of the gas-making fluid passing therethrough into said fuel bed.

In testimony whereof I affix my signature.
